CLINTON MILES WEEKS AND HARRY NORTON JACKSON, OF BABYLON, NEW YORK.

SHORT-CIRCUITING ATTACHMENT FOR GAS-ENGINE IGNITERS.

1,107,000.

specification of Letters Patent. Patented Aug. 11, 1914.

Application filed December 1, 1911. Serial No. 663,254.

To all whom it may concern:

Be it known that we, CLINTON M. WEEKS and HARRY N. JACKSON, citizens of the United States, and residents of Babylon, in the county of Suffolk and State of New York, have invented a new and Improved Short-Circuiting Attachment for Gas-Engine Igniters, of which the following is a full, clear, and exact description.

Our invention relates to means for grounding the igniters by means of which the charges are exploded in the cylinders of multi-cylinder internal combustion engines, for the purpose of determining whether or not any of the cylinders are failing to work, and which particular cylinder with the igniter therein is defective in operation or entirely out of commission, owing to the fouling or short-circuiting of the spark points inside of the combustion chamber, or from any other cause.

It is customary when running internal combustion engines of more than one cylinder to short-circuit or ground all of the jump spark plugs thereof except one, when the operator has reason to believe that some of his plugs or the cylinders in which they are mounted are out of order. If the single plug which is kept in operation continues to fire the charge in the cylinder to which it belongs, the operator knows that this plug is in proper condition, and that the cylinder containing it needs no further attention. He then short-circuits this plug also and removes the short-circuiting device from one of the other plugs and tests this last plug and cylinder in their turn in the same manner. In this way he will eventually discover which plug and cylinder, if any, are not working properly, in order to locate the real cause of the trouble.

Prior to our invention various short-circuiting devices in the form of switches have been employed for the above-described purpose, but it is the primary object of our invention to provide a short-circuiting device by means of which any given spark plug can be grounded, which is simple in construction, which can be cheaply made, and which may be applied to a high tension igniter at an instant's notice, without disturbing or rearranging in any way the regular connections which lead from the source supplying the igniter with electric energy, and which can be removed at once when the necessity for its use is no longer present.

Reference is to be had to the accompanying drawings forming a part of this specification, in which the same characters of reference indicate the same parts in all the views.

Figure 1 represents in vertical elevation a spark plug of the ordinary type with our improved short-circuiting attachment in place thereon; Fig. 2 represents a perspective view of our improved short-circuiting attachment; and Fig. 3 represents a vertical section on the line 3—3 of Fig. 2.

On the drawings the numeral 1 represents a portion of the cylinder of an internal combustion motor having a threaded opening to receive a bushing 2 of a spark plug of the ordinary type having a grounded spark point 3, and a high tension electrode stem 4 terminating in proximity to the spark point 3, and mounted in an insulating sleeve 5. This insulating sleeve 5 is held in the bushing 2 by means of a nut or gland 6, and the sleeve 5 is surmounted by a metallic cap 7 in electrical connection with the stem 4, and has a head 8 to which is secured one end of a high tension conductor 9. This conductor carries high tension current to bridge the gap between the point 3 and the end of the stem 4, and completes the circuit through the frame of the machine back to the source of supply in the usual way.

The short-circuiting attachment which we have devised comprises a pair of pivoted jaws 10 and 11, having bent-over ears which are perforated to receive a pivot pin 12, a spring 12' surrounding this pivot pin and engaging the two jaws 10 and 11 above the same in the position shown in Fig. 1, to force the jaws 10 and 11 together. The ends of the jaws 10 and 11 adjacent the pivot pin 12 are provided with diverging handles covered with insulation 13, said handles serving to permit the opposite ends of the jaws 10 and 11 to be forced apart against the power of the spring 12' when the attachment is to be applied to a spark plug which is to be put out of operation.

The jaw 10 is substantially straight, but the jaw 11 is bent outward from the jaw 10, as shown at 14, and then bent as shown at 15, to be substantially parallel to extend in a direction that makes an acute angle with the jaw 10, and has its inner end then bent inward, as shown at 16, the terminal edge of the portion 16 having a notch 17 formed therein. The jaw 11 is also shorter than the

jaw 10, the former being adapted to contact with the metallic portion of the top of the plug, and the latter being intended to be in contact with the body of the plug comprising the bushing 2 and the gland 6.

The manner in which the short-circuiting attachment is applied to a plug will be readily seen upon an inspection of Fig. 1. The operator presses the handles 13 together, spreading the jaws 10 and 11 apart, and then puts them into position to grip the top of the insulating sleeve 5 having the metallic head thereon, between them. In this position the in-bent portion 16 of the jaw 11 will fit under the lower shoulder of the metallic cap, the notch 17 receiving a portion of the side of the insulating sleeve 5, and the corner of the outward-bent portion 14 resting upon the head 8 of the stem 4. The jaw 10 extends downward, contacting with the side of the cap 7 near the upper edge, and touching adjacent its lower end upon the gland 6 and bushing 2 if long enough. As a result, when the short-circuiting attachment is in this position, any high tension current flowing over the conductor 9 will, instead of jumping over to the spark point 3, over an air gap of considerable resistance, take the path of lower resistance through the metallic jaws 10 and 11 to the gland 6, the frame of the machine, back to the source of supply. This will prevent the plug from sparking for the time being.

On a four-cylinder engine for example, three of our short-circuiting attachments will be used when it is desired to ascertain if one of the cylinders is working defectively or if any one of the spark plugs is fouled or otherwise out of order. When three of the plugs are short-circuited, the fourth will continue working, exploding the charges in the remaining cylinder, and the engine will keep running, if the ungrounded plug and the cylinder containing it are in good condition. The operator next grounds this plug and tests the second one, and so on, until he comes to the plug which is fouled or dirty, whereupon the engine will slow down 50 and stop; and the same result will follow if the plug is clean but something is wrong with the cylinder. He then knows that this last plug or the cylinder in which it is mounted needs attention, and he can at once 55 proceed to obviate the trouble and restore normal working conditions for the engine.

If the failure of the cylinder to work be due to the condition of the spark points 3 and 4, the operator can of course wipe the 60 spark points clean and restore the plugs to position; but if the failure of the cylinder to work be due to some other cause than the condition of the ignition system, the operator will of course have to investigate further. If, when the plug is taken out, the

points are found to be clean, this fact will be a sufficient indication that the fault lies in some other part, such as the carburetor, the valves, or perhaps the lubrication, and the operator will have to look for the trouble 70 until he finds it.

It will be observed from the above description that our improvement is simple in construction and can be readily made. It can be applied to any ordinary form of 75 spark plug now in use without having to give the binding post attachment on the top thereof any especial shape, and without having to break, disturb or rearrange the high tension connections. As stated above, they 80 will be sold in sets of three for four-cylinder engines, or in general sets of one less than the number of cylinders of the engine to which they are to be applied. They can be kept in the chauffeur's tool box; can be put 85 into use at a moment's notice to find which particular plug is defective, and can be removed as soon as the trouble has been located, without interfering with the short-circuiting connections in any way at all. 90

While we have shown and described our improved short-circuiting attachment as being adapted to jump spark plug structures, it is obvious that we may use it on make-and-break igniters, such as magnetic plugs, 95 as well.

We wish to have it understood that we reserve to ourselves the right to make such small changes in the shape, size and arrangement of the parts of our improvement 100 as fairly fall within the scope and spirit of our invention.

Having thus described our invention, we claim as new and desire to secure by Letters Patent:

1. A short-circuiting attachment for internal combustion engines comprising a pair of jaws pivoted at spaced distances from their extremities, said jaws being formed of sections bent at obtuse angles, the extremities of the jaws forming handles, one of the jaws at the opposite side of the pivot being continuously rectilinear and longer than the other jaw and the portion of the other jaw at the same side of the pivot being bent outwardly to provide a substantially hook-shaped portion as and for the purpose described. 110

2. A short-circuiting attachment of the class described embodying a pair of pivoted jaws, said jaws having extensions at one side of the pivot and normally spaced apart, grasping portions of insulating material mounted on said extensions, one jaw being straight and longer than the other jaw to 120 engage and bridge the gap between the outer end of the insulated electrode of an igniter and the body thereof and the other jaw being bent outwardly to provide a shoulder to 125 engage the outer end of an igniter, and hav- 130

ing its remaining portion bent downwardly and inwardly, said inwardly bent portion having a terminal notch to conform to the insulating sleeve of the igniter beneath the cap of the latter, and means normally holding the jaws in contact and the grasping portions separated.

In testimony whereof we have signed our

names to this specification in the presence of two subscribing witnesses.
